(57) **CLAIM**

The ornamental design for a luminaire, as shown and described.

DESCRIPTION

FIG. 1 is a perspective view of the design of the present invention for a luminaire;

FIG. 2 is a left side elevational view of the design of the luminaire of FIG. 1, of which the right side is a mirror image thereof;

FIG. 3 is a top plan view of the luminaire of FIG. 1;

FIG. 4 is a bottom plan view of the luminaire of FIG. 1; and,

FIG. 6 is a front elevational view of the luminaire of FIG. 1.
